UNITED STATES PATENT OFFICE.

WILLIAM ERASTUS WILLIAMS, OF WILMETTE, ILLINOIS, ASSIGNOR TO DITTO INCORPORATED, OF CHICAGO, ILLINOIS, A CORPORATION OF WEST VIRGINIA.

GELATIN-ROLL SPINDLE.

Application filed March 11, 1925. Serial No. 14,840.

My invention relates to a roll of a gelatin sheet that is used in making copies on what is known as the hectograph principle.

The object of my invention is to furnish a form of roll that may be conveniently handled and that will cost less money in making, mounting and handling than has heretofore been used with gelatin rolls.

A further object of my invention is to provide a spindle upon which the gelatin roll is mounted in its use in a machine where rolls of this kind are used.

Reference will be had to the accompanying drawing in which Fig. 1 is an elevation 15 of one of my rolls mounted on a spindle.

Fig. 2 is a longitudinal sectional elevation of what is shown in Fig. 1.

Fig. 3 is an elevation of a middle portion 20 of the roll spindle showing the attachment of the roll to the spindle.

Fig. 4 is a section on line 4—4 of Fig. 3.

Fig. 5 is a plan view of the end of the roll sheet both ends being alike.

Fig. 6 is a section on line 6—6 of Fig. 1.

Fig. 7 is an end view of the spindle being what amounts to an end of either end of Fig. 1 or Fig. 2.

Fig. 8 shows a wooden spindle.

These gelatin rolls are made with a paper 30 or cloth backing on which there is provided a gelatin composition face on one side.

They are made in widths suiting the widths desired to be used in copying work, of varying widths ranging from nine to 35 twenty inches.

They are made in various lengths, but the usual length is about 15 feet and when this sheet of gelatinized fabric is rolled up it makes a roll of approximately four to four 40 and one-half inches in diameter.

It is customary in the use of these rolls to use them in a machine and the rolls are mounted on spindles one at each end of the sheet to which the sheet is permanently attached, as has heretofore been the general custom.

Thus each time a roll is manufactured and shipped for use there goes along with it two spindles which have become a part, as it 45 were, of the roll itself in service.

With my roll, I provide what may be termed permanent spindles that remain with the machine in which the rolls are used, and the rolls themselves as made by the manu-

facturer are mounted upon temporary 55 spindles usually made of paste board and used only for handling and transmission to the user of the rolls.

When the rolls reach the customer he unwinds the rolls from the shipping spindle 60 onto the service spindles of the machine, and I provide a peculiarly meritorious design for the ends of the roll sheets that adapt them to this handling and transfer from the temporary sheet spindle to the permanent service 65 spindle and thus I save the cost of what has heretofore been the practice of shipping with each new roll the two service spindles.

I accomplish this advantage by providing 70 the ends of the roll strips with end or tuck straps adapted to engage the spindles in the winding operation and adapted to form a closure for the loose end of the roll sheet when the same is wound upon itself to complete 75 form.

In the drawing, 1 indicates the main body 80 of the gelatin roll, which is fastened by a seam 2 to a cloth end 3 adapted to be the armor or protecting coating around the roll when the same is wound up.

This cloth length is sufficient to a little more than entirely enwrap the entire circumference of the gelatin roll when the same is wound up.

On the end of this cloth end of the roll 85 sheet I provide a strap end 4 and at a distance back from the end of the cloth end amounting to the circumference of the wound up roll, I provide a keeper piece 5 sewed onto the cloth 3 underneath which the 90 end of the strap 4 may be tucked as shown in Fig. 1, in order to hold the roll from automatically unwinding.

The keeper piece 5 is slotted at 6 so that 95 the end of the strap 4 may be inserted at this slit as is shown in Fig. 1, or the strap may be inserted under the edge of the keeper piece 5 at the edge thereof as indicated by 7.

The purpose of this slit 6 in the keeper piece 5 is to permit the strap to be engaged thereby when the roll is a little larger or a little smaller due to the swelling or the shrinking of the gelatin under the influence of more or less moisture.

The service spindle is indicated as 8 being 105 a tube provided with end flanges 9 permanently secured thereto and provided with a diameter slightly larger than the largest

diameter of the roll as a body indicated by 10, the single web of this roll being indicated by 1 as before mentioned.

The end flanges 9 are sufficiently large to 5 allow the spindle with a roll mounted thereon to be laid on the table or on the floor or any suitable position without the roll body 10 getting in contact with the floor or being distorted or injured when several rolls are 15 run down a chute guided by end flanges 9 of the spindles.

The end flanges 9 and the ends 11 of the 15 tubular spindles are notched out at 12 for engagement with the driving mechanism of 20 the machine in which the rolls are used.

The central portion 13 of the tubular spindle 8 is made smaller in diameter to permit the winding thereon of the strap ends 4 without causing a bulge in the body of 25 the gelatin portion of the sheet when it is wound upon the spindle.

This portion 13 of the spindle 8 is slotted by slots on opposite sides as is indicated by 14 for the purpose of engaging the strap 25 ends 4 to start the winding of the roll sheet onto the spindles and this is accomplished easily by simply tucking the end of the strap 4 into this slot and starting the winding of the roll sheet in the absence of 30 any great friction until the strap has been wound upon the spindle portion 13 sufficient to generate enough friction to hold the strap and roll sheet firmly to the spindle portion 8 for the service required.

35 Thus in the use of my roll as provided the roll is shipped on a temporary spindle and then at the machine is rewound onto the service spindle 8 and then in the service of the roll and the roll is used in the copy 40 work it is wound from one service spindle onto another commencing with a vacant spindle upon which there will then accumulate the used roll until the entire roll is on that spindle leaving vacant the first spindle 45 which is then ready for receiving a fresh roll upon it as the fresh roll is used in the service of the machine.

These service spindles 8 are made sufficiently substantial to stand a continual service 50 in the use of a machine of this class and a sufficient number of them is provided to carry all the rolls that any given user may desire to use from day to day in this copy work.

55 The shape and construction of the roll web or sheet as described permits the use

of these service spindles and saves the expense of the regular service spindles that heretofore have been shipped and used only with a single roll; when that roll is worn out it has been the practice heretofore to not only discard the used up roll but often also the service spindle which went with it.

Thus by my invention I bring about a great economy in the use of these gelatin 65 copy rolls.

The service spindles with their flanges 9 which permit the spindles as individuals to be rolled down a chute and a stock of them 70 carried in a chuteway with the rolls mounted on the spindles, permits the storage and handling of rolls in a more compact and convenient way than has heretofore been accomplished by any means known to me.

When spindles are desired without the 75 end flanges and with the old style end gudgeons heretofore used, I provide the spindle in the form of Fig. 8 which may be made of wood and be made smaller in the center as indicated by 15, and be provided 80 with a slot 16 through the body similar to slot 14 and used in the same way.

The novel spindle claimed in this application is also shown in my co-pending applications Ser. Nos. 26,777; 54,750; and 85 108,058; and the right to claim this novelty is expressly reserved.

What I claim is:—

1. In a spindle of the class described, the combination with a central tubular body 90 portion, of annular ends of relatively thin material having outwardly extending concentric internal and peripheral flanges, said internal flanges fitting over and rigidly united to said body portion, with terminally 95 open notches through said internal flanges and body portion.

2. A gelatin roll spindle having a central cylindrical portion joined to terminal body portions by outwardly flaring conical portions, a longitudinal slot in said central portion and terminal winding teeth, and annular ends, each having an outwardly extending internal flange fitted over said body, rigidly united thereto and having winding teeth 100 continuous with said first mentioned teeth, and a peripheral outwardly turned supporting flange serving to protect said teeth.

Signed at Chicago, in the county of Cook and State of Illinois, this 5th day of March, 11 1925.

WILLIAM ERASTUS WILLIAMS.
